United States Patent

Des. 235,495
Patented June 24, 1975

235,495

SECTIONAL SOFA

Harry Laylon, Syracuse, N.Y., assignor to Dart
Industries Inc., Los Angeles, Calif.

Filed Mar. 2, 1973, Ser. No. 337,709

Term of patent 14 years

Int. Cl. D6—01

U.S. Cl. D6—63

FIG. 1 is an exploded perspective front view of a sectional sofa embodying my new design; and
FIG. 2 is a perspective front view of the sectional sofa.

I claim:
The ornamental design for a sectional sofa, substantially as shown.
